UNITED STATES PATENT OFFICE

SAMUEL MARCUS, OF BROOKLYN, NEW YORK, ASSIGNOR, BY MESNE ASSIGNMENTS,
TO MARKON MANUFACTURING CO. INC., OF NEW YORK, N. Y., A CORPORATION OF
NEW YORK

EYE SET

Application filed January 26, 1927. Serial No. 163,610.

This invention relates to an eye set, the same being in the nature of an improvement upon the eye set shown and described in the pending application of Alexander Konoff,

5 Serial No. 161,915, filed January 18th, 1927, and an object of the present improvement is to provide an eye set which is of extremely simple and inexpensive construction and the parts of which are so arranged that an eye 10 set of a given size is adaptable for use in doll heads of widely varying proportions without the exercise of any care upon the part of an operator engaged in attaching the eye sets in the differently proportioned heads.

15 A further object is to provide means whereby the two eye balls of the eye set may at no time in use rest in objectionably tight contact with the eye sockets of the head, and whereby the eye set is permitted a slight but 20 free tilting movement in a horizontal plane to insure against a greater degree of tightness of one of the eye balls than the other against its socket.

A further object is to provide an improved 25 attaching member for eye sets so constructed as to include parts for engaging the doll head and which are positively locked against disengagement from the doll head and which at the same time provide for a suitably free 30 tilting movement of the eye set upon a vertical axis mid-way between the two eye balls.

Other objects and aims of the invention, more or less specific than those referred to above, will be in part obvious and in part 35 pointed out in the course of the following description of the elements, combinations, arrangements of parts and applications of principles constituting the invention; and the scope of protection contemplated will 40 be indicated in the appended claims.

In the accompanying drawings which are to be taken as a part of this specification, and in which I have shown merely a preferred 45 form of embodiment of the invention:

Fig. 1 is a rear view of an eye set constructed in accordance with this invention, and showing the same in position within a doll head, the doll head being illustrated in 50 vertical section.

Fig. 2 is a horizontal sectional view taken upon the plane of line II—II of Fig. 1.

Fig. 3 is a vertical sectional view taken upon the plane of line III—III of Fig. 1.

Fig. 4 is a vertical sectional view taken 55 upon the plane of line IV—IV of Fig. 1.

Fig. 5 is a view similar to the central portion of Fig. 4 but illustrating the attaching member as it appears just prior to its movement into final attaching position, the final 60 attaching position being illustrated in Fig. 4.

Fig. 6 is a plan view showing the blank from which the attaching member is formed, and

Fig. 7 is a detail sectional view through the 65 attaching member, the section being taken substantially upon the plane of line VII—VII of Fig. 4.

Referring now to the drawings for a detailed description of the exemplary structure illustrated therein, the reference character L indicates a doll head or the like, the same being hollow as usual and having the spaced eye sockets 1 and 2 at opposite sides of the central or nose portion 3. 70

Interiorly of the head, and at the rear of the central or nose portion 3 there is provided a pair of inwardly projecting lugs as 4 and 5 spaced at opposite sides of a line extending horizontally between the centres of 80 the eye sockets 1 and 2 and thus providing an open recess as 6 between them through which may extend a horizontal cross rod as 7 which carries the two eye balls as G and H.

The lugs 4 and 5 may be provided in any 85 appropriate manner but are preferably molded as integral parts of the material of the doll head.

The eyes G and H may be formed of any appropriate material, such as celluloid, sheet metal, or otherwise. They consist essentially of hollow semispherical shells open at their rear sides and having an iris as 8 pictured in appropriate position upon the outer spherical surface. They are fitted upon the opposite 90 end portions of the cross rod 7, being formed each with diametrically opposite bearing openings 9—9 which loosely telescope over the cross rod so that the eyes are freely rotatable upon the cross rod and likewise freely 95 100

movable longitudinally of the cross rod. The bearing openings 9 are so disposed that the cross rod is held always in a position extending substantially horizontally through the spherical centres of the eye balls or shells so that rotary movement of the eyes about the cross rod will not alter the fit of the outer spherical surface of the eyes with relation to the eye sockets 1 and 2.

10 In order to cause rotation of the eyes upon the cross rod, as well as to insure simultaneous rotation of the two eyes, a Y-shaped operating member 10 is provided the opposite legs as 11 and 12 of which engage the eyes respectively and the stem 13 of which carries a suitable weight as 14 by which the operating member is gravity controlled to produce rotation, or more correctly, oscillation, of the eyes in response to movement of the doll head 20 between upright and reclining position, this movement being of course relative since it is in fact the doll head which moves while the eyes are maintained relatively stationary through the gravity pull of weight 14.

25 The operating member 10 may be of any appropriate construction but as illustrated consists of two separate parts, one of said parts constituting one of the legs, as 11, and the stem 13 of the operating member, and 30 the other part constituting the remaining leg, as 12, of the operating member. These parts are shown each to consist of a strip of sheet metal and they are pivotally connected together at the point where they are connected 35 with the weight 14, each part having a suitable apertured enlargement through which the rivet or like fastening device as 15 extends for serving the double purpose of retaining the weight connected with the two parts and 40 of pivotally joining said two parts together. It is intended that the pivotal connection shall be suitably loose to permit free movement of the upper or eye engaging ends of the two parts or legs 11 and 12 toward and away 45 from each other. The upper ends of the legs are each provided with forwardly bent ears as 16 which are apertured as at 17 to loosely receive the cross rod 7 so that while said legs are positively connected with the cross rod 50 they are nevertheless free to rotate relative thereto and to move longitudinally therealong.

The upper end portions of the legs 11 and 12 are thus held in position spanning across 55 the rear open sides of the eye shells so that portions as 18 and 19 spaced above and below the ears 16 extend across the upper and lower rear edge portions as 20 and 21 of the eye balls or shells, said portions of the legs 60 and the edges of the eye shells being at all times in free rubbing engagement with each other so that while the legs 11 and 12 may freely slide along said edges during any movement of the eye shells or of the legs longitudinally of the cross rod said eye shells

are nevertheless securely held against any appreciable rotary movement upon the cross rod without a corresponding movement of the operating member.

In order to retain the legs 11 and 12 of the 70 operating member properly centered with respect to the eye shells the shells are preferably formed with shoulders as 22 and 23 at their rear edges projecting rearwardly of the plane of the edge surfaces 20 and 21 and 75 adapted thereby to engage opposite sides of the portions 18 and 19 to thus prevent any objectionable movement of the eyes longitudinally of the cross rod without corresponding 80 movement of the connected leg of the operating member.

If desired the parts of the operating member may be formed of spring material, and the upper end portions as 24—24 of the two legs 11 and 12 may be extended above the upper margins of the eyes and cut away as at 25—25 so as to thus render them highly resilient 85 for thereby operating as resilient bumpers adapted to engage against portions as 26 of the doll head to limit relative movement of the eyes in one direction. Likewise the stem portion 13 may be extended downwardly below the weight 14 and be cut away as at 27—27 so as to render the lower end portion as 28 highly resilient for thereby operating as a resilient bumper adapted to engage against a portion as 29 of the doll head for resiliently 95 limiting movement of the eyes in a direction opposite to that limited by the bumpers 24—24.

Also if desired the legs 11 and 12 may be cut away at suitable points as at 30—30 to thereby provide localized regions of weakness adjacent the respective eyes at which points the legs 11 and 12 may be readily bent whenever it is desired to adjust the eyes relative to each other rotatably upon the cross rod.

Also if required the legs 11 and 12 may be provided with stiffening ribs as 31—31 by which to stiffen the legs at points between the weight and the weakened regions defined by the cuts 30—30.

While it will of course be understood that eye shells having a supporting cross rod and an operating member as above set forth may be supported in operable position within the doll head by any appropriate means regardless of how the cross rod is connected with the head, nevertheless, in attaching such eyes within doll heads having the central or nose lugs 4 and 5 as above referred to it is proposed that a specially formed attaching member as 32 may be employed, said attaching member being connected with the cross rod and being adapted to be inserted in position between the lugs 4 and 5 to retain the cross rod in its proper operative position.

The attaching member 32 herein illustrated is formed from a single piece of sheet material, preferably sheet metal, the blank of 130

which is illustrated in Fig. 6 wherein it will be seen to consist of a central or base portion 33, opposite side wall portions 34 and 35 and opposite end wall portions 36 and 37.

5 The side and end wall portions are integral with the base portion and, in the completed article, are bent relative thereto on lines 38-38 so as to define a rectangular structure. In bending down the side wall portions 34 and 10 35 said portions are bent into right angular relationship with the base portion so as to stand in substantially parallel relation to each other. In bending down the end wall portions 36 and 37 said portions are bent to and 15 beyond right angular relation to the base portion so as to stand in inclined positions converging toward each other away from the base, see Fig. 5. The end wall portions are thus positioned directly between the side wall 20 portions.

The side wall portions are formed with bearing openings 39-39 therethrough through which the cross rod 7 extends, it being here noted that in use the attaching member 25 is placed between the nose lugs in a position so that the base portion 33 thereof is spaced back of the cross rod, that is with the side and end wall portions projecting forwardly into the recess 6 and toward the front 30 or face side of the doll.

The forward or free edges as 40 and 41 of the end walls 36 and 37 are provided with tangs 42 and 43 respectively said tangs being bent outwardly and being adapted to be 35 driven into the opposing wall surfaces 44 and 45 of the nose lugs 4 and 5 respectively, by bending or swinging the end wall portions 36 and 37 outwardly to or near right angular relationship with the base portion 33, after 40 the attaching member has been inserted into the recess 6.

The side wall portions 34 and 35 are provided with shoulder parts 46-46 arranged to hold the end wall portions spread apart in 45 operative position, as seen in Fig. 4.

By reference to Fig. 7 it will be seen that the shoulder parts 46 each provides an inclined surface as 47 leading thereto and that the normal position of the end wall portions 50 is relatively behind said inclined surfaces. When the attaching device is being connected in position between the nose lugs the end walls 36 and 37 are forced away from each other over the inclined surfaces 47-47, the side wall 55 portions 34 and 35 meanwhile resiliently yielding sufficient to permit passage of the end walls over said inclined surfaces. As soon as the end walls have moved sufficiently apart the side walls snap together and present 60 the shoulders 46-46 behind the end walls and thereafter prevent retrogressive movement of the end walls and thus retain the tangs in positive engagement within the nose lugs.

Any suitable tool may be employed for 65 moving the end walls apart to drive the tangs

thereof into the nose lugs, and for this purpose the drawing Fig. 5 illustrates by dot and dash lines a simple tool consisting of two parts as 48 and 49 inserted through openings as 50 and 51 provided for the purpose through the base portion 33, the part 48 being adapted to engage the wall 36 and the part 49 being adapted to engage the wall 37, and said two parts being intended to be spread apart to thereby also spread said walls.

It is a feature of this invention to provide means for guarding against a too tight engagement of the eye balls or shells against the eye sockets of the head when the operation of attaching the eye set has been completed, and to this end it is noted that when the eye shells are initially presented into the eye sockets, and the attaching member presented into the recess 6, the attaching member is in the condition indicated in Fig. 5, that is with the end walls 36 and 37 inclining toward each other from what will now be termed spaced pivots as 52 and 53 co-inciding with the lines 38 by which said end walls are connected with the base portion 33, and that in bending these end walls away from each other into parallelism, as in Fig. 4, for driving the tangs 42 and 43 into the nose lugs, the base portion 33, and consequently the side wall portions 34 and 35 will be eased backwardly, and in addition to this it is noted that the tangs 42 are not at right angles to the end walls but on the contrary are inclined with respect to said end walls so that they will operate to cam, or wedge, the entire attaching member backwardly as they are driven into the material of the lugs.

From this it will be seen that in bending apart the end walls of the attaching member and driving the retaining tangs into the lugs said action will necessarily result in a backward movement of the side walls of the attaching member, and a consequent easing of the eye shells away from the eye sockets of the head, a distance determined by the inclination of the end walls toward each other upon the pivots 52 and 53 at the moment when the retaining tangs are presented against the surfaces 44 and 45 of the lugs and the degree of inclination of the lugs with respect to said end walls.

Due to the fact that each of the end walls of the attaching member provides only a single retaining tang for engaging the nose lugs, and to the fact that these tangs are aligned spaced apart above and below the horizontal plane of the cross rod 7, it follows that the attaching member, and consequently the cross rod and the eyes carried thereby, are capable of a tilting movement upon a vertical axis extending through said tangs. Accordingly, it will be impossible for one eye to be tight within its socket and the other loose since in this event the entire eye set would tilt upon the tangs and thereby automatically adjust the

eye set to relieve the objectionable tightness of one of the eyes.

If for any reason it should become necessary to remove an eye set from a head it is simply necessary to introduce a tool, similar to that already described, and swing apart the side walls 34 and 35 of the attaching member a sufficient distance to remove the shoulders 46-46 from behind the end walls 36 and 37. The end walls will be immediately free to return to their original inclined position, thereby withdrawing the tangs from the lugs and thus releasing the eye set, it being noted that the material from which the attaching member is formed is sufficiently springy to accomplish this result.

As many changes could be made in this construction, without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

1. An eye set comprising a pair of eyes, means connecting said eyes together, attaching means for attaching said connecting means with a doll head, and said attaching means having vertically arranged pivot parts for engagement with the doll head to thereby support the eye set for adjustment upon a vertical axis.

2. An eye set comprising a pair of eyes, a cross rod extending between and connecting said eyes, an attaching member engaging the cross rod intermediate the eyes, said attaching member having wall portions arranged above and below the cross rod and movable away from each other, and pivot forming means provided upon said wall portions adapted to engage spaced parts of a doll head when said wall portions are moved away from each other whereby to pivotally support the eye set for automatic adjustment upon a vertical pivot.

3. An eye set comprising a pair of eyes, a cross rod extending between and connecting said eyes, an attaching member engaging the cross rod intermediate the eyes, said attaching member having opposite wall portions pivotally connected therewith adapted to swing from a position converging toward each other to a position substantially parallel with each other, and doll head engaging means carried by said wall portions adjacent the free edges thereof by which to fix the attaching member in position within a doll head, together with other means comprised in said attaching member for holding said wall portions swung into their parallel position.

4. An eye set comprising a pair of eyes, a cross rod extending between and supporting said eyes, the eyes being rotatable and

slidable upon said cross rod, operating means for said eyes comprising a pair of members connected with said eyes respectively, means pivotally connecting said members together, a weight carried by said members collectively, one of said members providing a bump portion extending beyond the weight, each of said members providing bumper portions extending beyond the eyes, and both of said members being formed of spring material.

5. An eye set comprising a pair of eyes, a cross rod extending between and supporting said eyes, the eyes being rotatable and slid able upon said cross rod, operating means for said eyes including a weight, members extending from the weight to said eyes respectively each of said members having a portion providing an opening through which the cross rod extends to thereby slidably and rotatably connect said members with the cross rod, each of said members also having parts engaging the eyes to cause simultaneous rotation of the eyes with said members, each of said members comprising a flat strip of sheet metal and each having portions of reduced width whereby to define regions of weakness where said members may be readily bent for thereby adjusting the eyes with respect to each other.

6. An eye set comprising a pair of eyes, a cross rod extending between and supporting said eyes, the eyes being rotatable and slid able upon said cross rod, operating means for said eyes including a weight, members extending from the weight to said eyes respectively each of said members having a portion providing an opening through which the cross rod extends to thereby slidably and rotatably connect said members with the cross rod, each of said members also having parts engaging the eyes to cause simultaneous rotation of the eyes with said members, each of said members comprising a flat strip of sheet metal and each having portions of reduced width whereby to provide suitably resilient parts to serve as bumpers for limiting the weight controlled movements of the eyes.

7. An eye set comprising a pair of eyes, a cross rod extending between and connecting said eyes, an attaching member engaging the cross rod intermediate the eyes, and said attaching member having portions arranged above and below the cross rod and movable away from each other together with pivot forming means provided upon each of said mentioned portions for engaging spaced parts of the doll head when said portions are moved away from each other to thereby pivotally support the eye set for movement upon a vertical pivot.

8. An eye set comprising a pair of eyes spaced apart, attaching means arranged in the space between the eyes by which to connect the eyes with a doll head, means by which

said attaching means is connected with the eyes, said attaching means including a pair of members spaced apart one above and the other below the horizontal plane of a straight line between the centres of the eyes, and pivot forming means carried by said pair of members projecting away from each other one upwardly and the other downwardly, together with means whereby said pair of members are movable to cause said pivot forming means to engage opposing portions of the doll head for providing pivotal connection of the eyes with the head about a vertical axis.

9. An eye set comprising a pair of eyes spaced apart, attaching means arranged in the space between the eyes by which to connect the eyes with a doll head, means by which said attaching means is connected with the eyes, said attaching means having vertically arranged pivot parts disposed one above and the other below the horizontal plane of a straight line between the centres of the eyes engaging spaced portions of the doll head for providing pivotal connection of the eyes with the head about a vertical axis.

10. An eye set comprising a pair of eyes spaced apart, attaching means arranged in the space between the eyes by which to connect the eyes with a doll head, means by which said attaching means is connected with the eyes, said attaching means having vertically arranged pivot parts disposed one above and the other below the horizontal plane of a straight line between the centres of the eyes movable into engagement with spaced portions of the doll head for providing pivotal connection of the eyes with the head about a vertical axis, together with means for retaining said pivot parts in engagement with the doll head.

11. An eye set comprising a pair of eyes, a cross rod upon which the eyes are mounted spaced apart, attaching means for connecting said eyes with a doll head, and said attaching means having vertically arranged pivot parts adapted to be projected into embedded relation with parts of a doll head in a plane transversely of the cross rod to thereby support the eye set for adjustment upon a vertical axis.

In testimony whereof I affix my signature.
SAMUEL MARCUS.
